CLAIM

The ornamental design for a football with soccer ball pattern, as shown and described.

DESCRIPTION

FIG. 1 is a side perspective view of a football with soccer ball pattern;

FIG. 2 is a top plan view thereof;

FIG. 3 is a bottom plan view thereof;

FIG. 4 is a left side elevational view thereof;

FIG. 5 is a right side elevational view thereof; and,

FIG. 6 is an end elevational view thereof.

The broken lines in FIGS. 3 and 5 are included for the purpose of illustrating an element of the football with soccer ball pattern that forms no part of the claimed design.
